UNITED STATES PATENT OFFICE

2,632,403

RAILWAY PILOT STRUCTURE

Adelbert C. Wintemberg, Drexel Hill, and Greenville E. Jones, Lansdowne, Pa., assignors to General Steel Castings Corporation, Granite City, Ill., a corporation of Delaware

Application November 1, 1947, Serial No. 783,460

3 Claims. (Cl. 105—2)

1

The invention relates to railway vehicles and particularly to the front end structure of a locomotive including a pilot and a coupler movable from an extended operative position to a retracted position within a recess in the pilot.

One object of the invention is to close the opening in the pilot at the forward end of the coupler receiving recess after retracting the coupler into the pilot by providing a pair of swinging doors movable independently of the coupler and retractable wholly within the pilot when not in use with no portion of the doors projecting beyond the forward face of the pilot.

Another object is to provide a pilot which is shorter than and has a smaller opening in its forward face than pilots used heretofore for retractile couplers.

Other objects will be apparent to those skilled in the art from the following description and accompanying drawings in which:

Figure 1 is a top view and partial horizontal section taken approximately on the line 1—1 of Figure 3 and shows a locomotive front end structure constructed according to the invention, the coupler extending forwardly in operative position and the pilot doors being retracted within the pilot.

Figure 2 is a view similar to Figure 1 showing the coupler retracted within the pilot and showing the doors closing the coupler recess opening in the pilot.

Figure 3 is a longitudinal vertical section taken approximately on the line 3—3 of Figure 1.

Figure 4 is a front view partially broken away to show the door lower support.

Figure 5 is a vertical section taken approximately on the line 5—5 of Figure 2 and shows details of the door lower support and of the latch to hold the door in open position.

Figure 6 is a detail horizontal section taken on the line 6—6 of Figure 4.

The forward end of locomotive framing 1 mounts a pilot 2 having a coupler receiving recess 3. A yieldingly mounted coupler carrier 4 in pocket 3 supports the forward end of a coupler device 5 which includes a link 6 with bifurcated ends and a coupler 7. The rear end of link 6 is pivoted to a draft gear yoke 8 and its forward end pivotally mounts coupler 7.

Depending legs 10 on link 6 slide on carrier 4 which yieldingly supports the forward end of the link and the coupler. Coupler 7 extends forwardly of the pilot when in functioning position and may pivot horizontally and vertically

2

to accommodate relative horizontal and vertical movement of adjacent vehicles caused by curves and track irregularities.

Coupler 7 may be retracted wholly within 5 pilot recess 3 by pivoting link 6 and coupler 7 to the positions indicated in broken lines in Figure 2. Coupler 7 may be locked to link 6 in extended and retracted positions by a vertical pin 9 extending through link 6 and coupler 7 in 10 coupler extended position and through link 6 along in coupler retracted position. The coupler device described is the subject matter of a copending application of J. C. Travilla, Jr., filed 15 August 25, 1947, Serial No. 770,480, now abandoned and in itself does not constitute the present invention.

A pair of doors 11, 12 have inwardly extending arms 11a, 12a, respectively, and swing about vertical pins 13, 14, respectively, forming pivotal connections at the inner ends of the arms to the pilot horizontal wall 2a, from an operative position shown in Figure 2 in which the doors close the forward end of the coupler recess in the pilot when the coupler is retracted, 20 to an inoperative position shown in Figure 1 in which the doors are received wholly within the coupler pocket and allow the coupler to be moved to its extended functioning position forwardly of the pilot.

Each door 11, 12 has an inwardly extending 30 horizontal lower flange W above the level of the bottom edge of the door and provided with depending ribs 15 substantially throughout its length and with spaced apart lugs 16 spaced from ribs 15. When the doors are in open position, ribs 15 and lugs 16 form a channel between them to receive upstanding lugs 17 on the pilot and when the doors are in closed position, ribs 15 and lugs 16 straddle upstanding lugs 18 on the pilot. Lugs 18 cooperate with pins 13, 14 to resist rearward thrust of the doors when the doors are in closed position and strike an object in the path of the locomotive.

The doors are locked in closed position by a 45 latch 22 (Figure 6) pivoted to door 12 for movement in a horizontal plane. Latch 22 has a hook 23 at one end which fits into a lug 24 in door 11. A spring 25 urges latch 22 to locking position. The latch may be released by pulling forwardly on handle 26 attached to one end 50 of the latch.

Each door 11, 12 is locked in open inoperative 55 position by a latch 19 (Figure 5) pivotally mounted in the floor of the coupler pocket 3. Latch 19 is urged by a spring 20 to the position shown

in Figures 1, 3, and 5 in which the latch resists forward movement of the door to closed position. To close a door, the associated latch 19 is depressed below the door with one hand while the door is closed with the other hand. When the forward edge of the door passes over latch 19, the latch is held depressed by the door until the rear edge of the door passes forwardly beyond the latch, whereupon the latch will spring back into place. When a door is being moved from closed to opened positions, the associated latch 19 is depressed by the door as the door rides over the latch until the door abuts a stop 21 forming a part of rear lug 17, the latch then springs up and engages the front of the door.

By pivoting the coupler relative to the link to retract the coupler and by using a pair of doors to close the coupler recess opening as described, a shorter pilot and a smaller opening in the front of the pilot to receive the coupler may be used than is now used on locomotives with other retractile coupler arrangements and doors movable with the couplers. Also the doors are retracted wholly within the pilot when they are not being used.

The details of construction may be varied substantially without departing from the spirit of the invention, and the exclusive use of those modifications coming within the scope of the claims is contemplated.

What is claimed is:

1. In a railroad vehicle pilot, a front wall having an opening, a coupler receiving recess extending rearwardly of said front wall and having a top wall and a bottom wall merging with said front wall, an upright door for said opening having a rearwardly extending arm on its upper portion pivoted to said top wall and having an inwardly extending flange on its lower portion provided with depending elements spaced apart transversely of the door, upwardly extending lugs on said bottom wall received between opposing

faces of said door elements and forming a track on which said door may slide to and from said opening and forming stops positively resisting movement of said door transversely of its face when the door is in closed position.

5 2. In a railroad vehicle pilot, a front wall having an opening for a coupler, a horizontal wall extending rearwardly from said front wall below the level of said opening and having 10 upwardly lugs leading from a point spaced rearwardly from said wall near the center of said opening arcuately and outwardly from the longitudinal center line and rearwardly from said front wall, said horizontal wall and lugs forming a support for a sliding door, and said lugs forming spaced guides for the door.

15 3. A railroad vehicle pilot structure as described in claim 1 in which the track-forming elements on the bottom wall form an arcuate track guiding the door rearwardly and to the side of the coupler-receiving recess as the door is moved away from the opening in the front wall.

ADELBERT C. WINTEMBERG.
GRENVILLE E. JONES.
